UNITED STATES PATENT OFFICE.

JAMES THORNTON, OF WELLSVILLE, ASSIGNOR OF ONE-FOURTH HIS RIGHT
TO PRATT & LETCHWORTH, OF BUFFALO, NEW YORK.

IMPROVEMENT IN SAFETY-HOOKS.

Specification forming part of Letters Patent No. 174,592, dated March 7, 1876; application filed
December 3, 1875.

To all whom it may concern:

Be it known that I, JAMES THORNTON, of Wellsville, in the county of Allegany and State of New York, have invented certain new and useful Improvements in Safety-Hooks, which improvements are fully set forth in the following specification, reference being had to the accompanying drawing.

My invention relates to a device adapted to serve as a connection for parts of harness and for various other purposes; and it consists, generally, of a hook composed of two corresponding parts pivoted together, and constructed in such a manner that by inserting a strap or other stop between two of the jaws of the hook the opening of the latter will be prevented, as will be hereinafter more fully described.

Figure 1 is a perspective view, representing my improved hook as connecting the hame-strap to a hame. Fig. 2 is a plan view of the hook, with the hame and hame-strap in section. Fig. 3 is a longitudinal section, and Fig. 4 an end view of the hook. Fig. 5 is a plan view, representing the two parts of the hook detached from each other. Fig. 6 represents the hook open.

Like letters of reference refer to like parts in each of the figures.

A represent the two parts of the hook, resembling in shape the character or figure 3, and pivoted together at *a*, so as to be arranged symmetrically on opposite sides of the pivot. Each of the parts A consists of a grasping-jaw, *b*, and a locking-jaw, *c*, arranged on the same side of the pivot, the jaws *b* of both parts butting against each other, while the jaws *c* overlap each other, as clearly shown in the drawing. The overlapping jaws *c* slide one upon the other, and permit the jaws *b* to be

opened sufficiently to grasp the part with which the hook is to be engaged. Upon closing the jaws *b* their ends strike against each other, when the overlapping jaws *c* form a loop, in which a connecting strap, band, or other stop, *D*, is inserted, as shown in Figs. 1 and 2. This stop prevents the overlapping jaws from being closed, and consequently the opening of the jaws *b*. Upon withdrawing the stop *D* the hook is readily opened and disengaged from the part to which it was connected.

My improved hook is especially applicable in cases which require the hook to be frequently adjusted from one place to another—as, for instance, for connecting the hame-strap to the hame, as represented in Figs. 1 and 2. In this case the jaws *b* of the hook are engaged in one of the series of holes, *e*, in the hame *F*, and the hame-strap *D'* passed through the loop formed by the jaws *c*, thereby securing the hook firmly in place.

Upon withdrawing the hame-strap the hook is readily opened and adjusted higher or lower, as may be required.

My improved safety-hook is also applicable in numerous other ways—as, for instance, for connecting the handles to satchels—and is cheaply manufactured, while affording a most reliable means of connection.

I claim as my invention—

A safety-hook, composed of two parts, pivoted as shown, and provided with gripping-jaws *b* at one end, and overlapping jaws *c* at the opposite end, substantially as and for the purpose described.

JAMES THORNTON.
